DESIGN FOR A DRESS ENSEMBLE

Rose Feintuck, New York, N. Y.

Application July 30, 1937, Serial No. 70,731

Term of patent 3½ years

To all whom it may concern:

Be it known that I, Rose Feintuck, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The rear jacket portion of the dress ensemble is conventional.

The front section of the shoulder strap consists of two narrow strips caught at the top shoulder portion by the wide graduated rear strap in a looped formation.

I claim:

The ornamental design for a dress ensemble, substantially as shown, and described.

ROSE FEINTUCK.
